UNITED STATES PATENT OFFICE.

WILLIAM L. CALLAHAN, OF GARWOOD, NEW JERSEY, ASSIGNOR TO C. & C. ELECTRIC & MANUFACTURING COMPANY, A CORPORATION OF NEW JERSEY.

WELDING-HOOD.

1,191,562.

Specification of Letters Patent. Patented July 18, 1916.

Application filed October 5, 1914. Serial No. 865,030.

To all whom it may concern:

Be it known that I, WILLIAM L. CALLAHAN, a citizen of the United States of America, and a resident of Garwood, Union county, New Jersey, have invented certain new and useful Improvements in Welding-Hoods, of which the following is a specification.

This invention relates to improvements in welding hoods.

The object of the invention is to provide a shield or hood for the protection of the face and head of welding operators and adapted to be quickly put on and adjusted for each individual operator.

Other objects of the invention are to provide a light, well ventilated shield or hood having protecting pads for the face of the operator, and so arranged that the protecting eyeglasses may be swung outward or otherwise temporarily removed from the window of the hood to permit the operator to inspect the work with the naked eye and rest his eyes when the arc is not drawn without the necessity of removing the hood.

Other objects will appear as this specification proceeds while reference is had to the accompanying drawing in which—

Figure 1 is a side elevation of a welding hood embodying my invention. Fig. 2 is a top view of the hood. Fig. 3 is a horizontal sectional view through the window. Fig. 4 is a vertical central sectional view, and Fig. 5 is an enlarged detail sectional view of the window and a portion of the hood.

The hood comprises the curved face shield 6 and the top or head shield 7 preferably made of sheet metal and suitably joined by a locking seam 8, Fig. 5. The top shield 40 is provided with a ventilating duct 9 or there may be several such ventilating ducts. The hood is secured to the head of the operator by fastening straps 10 and 11 which are slotted to permit of adjustment by a lock screw or bolt 12. After the hood is put on, the operator slides the straps together until the hood sits firmly on his head after which he tightens the screw 12.

For the protection of the face and coöperating with the fastening straps there are provided two face straps 13 and 14 in the form of curved metal bands secured to the face shield by rivets 15 or otherwise.

13 is a forehead strap and 14 a chin strap

and both are padded with a lining 16 of 55 cork or other similar material.

The face straps also serve the purpose of preventing the cheek portions 17 from spreading or getting out of shape.

The operator observes his work through 60 a window opening 18 closed by a window containing colored glass to protect the eyes against the glare from the welding arc. The construction contains some of the features of the invention and is as follows: Surrounding the window opening 18 in the face shield there is a window casing 19, preferably an aluminum casting secured to the shield by rivets 20 and provided with hinge lugs 21, Fig. 2. The window comprises the 65 frame 22 which is also preferably made of aluminum for the sake of lightness and provided with hinge lugs 23 by means of which the window is hinged to the casing 19. 24 are springs, one on each side of the window 70 and secured to the shield as shown for keeping the window closed tightly against the casing 19. The window is further provided with a front flange 25 and from side to side of the window pass the rods 26 which serve 75 two purposes. First, they act as stops for the window against the casing 19 and second, they act as backing for the glass, see Fig. 5.

The glass is preferably made up of three 85 layers, of which 27, 27 are ruby colored and 28 is an intermediate layer of purple glass. Other colors of glass may be found useful to protect the eyes. The window frame is cut away as at 29 to permit the glasses to be 90 inserted from the one side.

30, 30 are flat springs secured to the front flange 25. The glasses are inserted behind the springs which press the glasses against the aforesaid rods 26 so that they are held 95 securely within the frame 22.

The hood as here described and illustrated is very light, yet furnishes adequate protection for the head of the operator. The duct or ducts 9 provide a means of escape from 100 the heated air around the operator's head within the hood and the heat from the electric arc causes additional air current so that the hood is at all times well ventilated.

During the work the window may be 105 opened as shown in dotted lines in Fig. 1 to permit the operator to inspect the work and rest his eyes. The springs 24 also serve

to maintain the window in its open position as is evident from the drawing.

The details of construction may be varied from that shown and described and I do not wish to be limited otherwise than the scope of the appended claim requires.

I claim:

The combination with a welding hood having an opening for observing the work, 10 a rectangular window casing secured to said hood and surrounding the said opening, a window frame hinged to the said window casing at the top thereof and provided with vertical front flanges on all sides thereof, 15 lateral rods in said window frame adapted to abut the said casing when the window is

closed, a plurality of differently colored glasses adapted to be inserted through an opening in the one side of said window frame, springs interposed between the said front flanges and the said glasses at the top and the bottom thereof for keeping said glasses in position against the said lateral rods and a spring on each side of said window frame and secured to the said hood for normally keeping the said window closed.

Signed at Garwood, New Jersey this 14th day of September, 1914.

WILLIAM L. CALLAHAN.
